UNITED STATES PATENT OFFICE.

CLIFFORD T. SAPPINGTON, OF FREDERICK, MARYLAND.

RECTAL APPLICATOR.

1,218,478.

Specification of Letters Patent.

Patented Mar. 6, 1917.

Application filed January 24, 1917. Serial No. 144,153.

To all whom it may concern:

Be it known that I, CLIFFORD T. SAPPINGTON, a citizen of the United States, residing at Frederick, in the county of Frederick and State of Maryland, have invented certain new and useful Improvements in Rectal Applicators, of which the following is a specification, reference being had therein to the accompanying drawing.

10 This invention relates to improvements in rectal applicators, one object of the invention being the provision of a sanitary device of this character, which is constructed from an integral piece of material and so shaped 15 as to carry thereupon a sheet of gauze or other unguent carrying material and to be naturally maintained within the rectum, so that the unguent is applied to the affected parts in the rectal canal, while the outer end 20 coöperates with the outer sphincter muscle, to prevent the unguent from soiling the clothes.

The present applicator is so constructed as to be easily inserted and withdrawn, and is 25 provided with a flexible soft shank, approximately the full length or slightly greater than the rectal canal, while upon one end is an egg-shaped inserting head, for disposition beyond the inner sphincter muscle, the 30 other end being provided with a disk shaped head, for disposition exteriorly of the outer sphincter muscle.

In the accompanying drawings:—

Figure 1 is a diagrammatical sectional 35 view through the rectum, showing the normal position of the present applicator.

Fig. 2 is a side elevation of the applicator, with the unguent carrying gauze in section.

Fig. 3 is a longitudinal section through 40 the complete applicator with the gauze attached.

Referring to the drawings, the numeral 5 designates the gauze carrying member, which is made of solid rubber, with the core 6 having 45 a covering of comparatively soft rubber and constructed so that the shank 7' is slightly flexible with a soft surface, so as not to injure the rectal canal, due to any involuntary contraction of the muscles about 50 the shank. The inserting head 8, which is egg-shaped with the point at the terminal, is integral with the shank and is composed of the same material, while the integral disk 9, upon the opposite end is formed with the 55 curved portion 10, which makes the shank

side of the disk slightly conical, and provides a face for contact with the outer portion of the outer sphincter muscle.

The shank 7 is made preferably the length, or slightly longer, than the rectal canal, so 60 that the inner sphincter muscle will contact the curved portion 11, at the junction between the head 8 and the shank 7', the inner and outer sphincter muscles, thus co-acting to hold the shank its length adjacent 65 to the rectal canal.

The unguent carrying member 12, is preferably a sheet of gauze or other absorbent material, and is adapted to be placed upon the member 5, with the edges 13 flared outwardly by the disk head 9.

Thus when the applicator has been inserted in the rectum, the portion of the gauze carrying the unguent and about the shank will supply the same to the walls of the rectal canal, and the two heads 8 and 9, due to the positions thereof, relatively to the inner and outer sphincter muscles will maintain the applicator in such desirable position. The applicator is readily removed, 80 and the gauze removed, and thrown away, while the member 5 may be washed with water and an antiseptic, so that a sanitary applicator is provided.

What I claim, as new, is:—

1. A rectal applicator comprising a relatively soft pliable body having a shank, and a head upon each end, and an unguent carrying sheet of absorbent material removably surrounding said body.

2. A rectal applicator comprising a relatively soft pliable body having a shank, and two heads, one upon each end, and an unguent carrying sheet of absorbent material surrounding one head and the shank, and 95 having its edges flared outwardly by the other head.

3. A rectal applicator comprising a relatively soft pliable body having an integral shank, egg-shaped and disk shaped ends, 100 and an unguent carrying sheet of absorbent material covering the egg-shaped end and the shank and having its edges flared outwardly by the disk-shaped end.

In testimony whereof I affix my signature 105 in presence of two witnesses.

CLIFFORD T. SAPPINGTON.

Witnesses:

D. GUY THOMAS,
J. HARRY KENNEDY.
